ABSTRACT OF THE DISCLOSURE

The relay has a contact-carrying tube movable linearly in one direction, within an annular space between an inner magnetic core and outer coil-carrying spool, in response to flux change produced by current in the coil. Return movement of the tube is caused by gravity and is retarded by the flux. The core and spool are positioned with respect to each other by complementary annular shoulders on the core and the spool. The core and spool are secured in this position and to a frame of the relay by engagement of an upper edge portion of the spool and a lower conical surface on the core with respective cooperating parts of the frame and a support plate which is secured to the frame.

BACKGROUND OF THE INVENTION

Field of the invention

An inductively-actuated electromagnetic motor acceleration relay wherein the movement of a contact-carrying member is inductively retarded to provide a time delay interval which varies in response to variations in the current flowing in an operating coil of the relay and wherein the force of inductive retardation is time-over-rideable by the force of gravity acting upon the contact-carrying member to cause operation of the relay even when there is little or no variation in the current flowing in the coil.

Description of the prior art

Various motor acceleration relays have heretofore been provided for controlling the commutation of the starting resistance in a motor circuit so that the current taken by the motor during acceleration does not exceed predetermined values.

One type of acceleration relay is described in U.S. Patent No. 1,980,736, issued Nov. 13, 1934 and in U.S. Patent No. 2,073,382, issued Mar. 9, 1937. Relays of this type are used in the so-called time-current system of motor acceleration and, when adjusted to provide proper acceleration of the motor under predetermined operating conditions, also provide, without change or adjustment, proper acceleration under different or even abnormal operating conditions.

As used in a motor acceleration system, these relays normally delay the successive energization of resistance commutating switches for periods determined by the magnitude of the current flowing to the motor, but if the motor fails to accelerate, or accelerates too slowly, the relays cause the next successive switch to be energized after a predetermined time regardless of the magnitude of the motor current. Such acceleration relays, responsive to both current and time, gained immediate market acceptance and are still in common use.

One of the disadvantages of the prior current-sensing time-limit relay resides in the manner of construction of the relay. The magnetic circuit of the prior relay comprises a central upstanding cylindrical core surrounded by a cast steel frame which is closed at the front and

2

open at the rear for ease of mounting on the front of a control panel. A spool member surrounded by an electromagnetic winding or coil is retained in the frame by a collar which is threaded into the top of the frame and urges the spool member against the bottom of the frame. The core of the prior relay has a lower threaded portion which is received, through a central axially-disposed opening in the spool member, in a complementary threaded opening in the bottom of the frame. A jam-nut, received on the threaded portion of the core and turned up against the outside face of the bottom of the frame, secures the core in position. The threaded connections provided in the prior relay not only add to the expense of manufacture, but also require that considerable care be exercised in assembly of the relays so as to obtain proper alignment of the relay components relative to each other.

An additional disadvantage of the prior current-sensing time-limit relay is that the coil is arranged for connection only from the rear of the panel on which the relay is mounted. The leads from the coil extend rearwardly through the rear opening in the frame and through the mounting panel for connection to other wiring on the rear of the panel. In controllers using the prior relay, the wiring between the components and the incoming or source leads, as well as the load leads, are connected on the rear of the panels. This is acceptable where floor space is ample and where the controller can be spaced from adjacent objects to permit convenient access to a workman for making connections on the rear of the panel.

Recently, however, demand has increased for controllers having electrical components arranged for wiring from the front of the panel. The prior time-current relay does not lend itself to front wiring because of the difficulty of bringing the heavy coil leads out to the front of the panel.

SUMMARY OF THE INVENTION

A current-sensing time limit motor acceleration relay in accordance with present invention has a spool member which has a downwardly directed shoulder in its central opening intermediate the ends thereof. The magnetic core of the relay is provided with an upwardly directed annular shoulder intermediate its ends and has a shallow conical portion at its lower end. The shoulders on the core and spool member position the core and spool with respect to each other. The conical portion of the core is received in a circular opening in a support plate which is removably secured to the bottom portion of a frame of the relay so that an upper edge of the opening engages the surface of the conical portion. In this manner, when the support plate is drawn into secured relationship with the frame, it urges the core and the spool member into firmly secured relationship with each other and at the same time urges an upper portion of the spool member firmly against the top portion of the frame. Thus, the improved structure of this invention eliminates the disadvantageous threaded connections between the core and frame of the prior art device and also inherently assures a properly aligned assembly, which proper alignment was achieved in the relay of the prior art only by selective adjustment.

The present invention additionally comprises a coil having terminals which are brought out toward the front of the relay thereby permitting the relay to be used on a controller where the wiring is arranged on the front side of the controller panel. Portions of the terminals extend outwardly through respective openings in a front cover of the relay, and the portions of the terminals interior of the cover receive a pair of bolts which are threaded into the terminals from the outside of the cover

to assist in supporting the coil. In this manner, the structure of the present invention provides a front-connectible relay thereby to solve an additional problem previously existent in the prior art.

BRIEF DESCRIPTION OF THE DRAWINGS

FIG. 1 is a perspective view of an electromagnetic relay in accordance with this invention;

FIG. 2 is an exploded perspective view of the relay of FIG. 1;

FIG. 3 is a top plan view of the relay of FIG. 1, a contact enclosing cover being removed;

FIG. 4 is a front plan view of the relay of FIG. 1, a portion of the contact cover and a contact housing being broken away; and

FIG. 5 is a sectional view taken generally along the line 5—5 of FIG. 4.

DESCRIPTION OF THE PREFERRED EMBODIMENT

Referring to the drawings, an electromagnetic current-sensing time-limit acceleration relay in accordance with this invention comprises a base 10 and a magnetic flux conducting frame assembly 11. The frame assembly includes a pair of side plates 14 and 15 and an upper wall or top plate 16, the side plates being preferably welded, one at each side of the top plate 16, as best illustrated in FIGS. 2 and 4, to form the generally U-shaped frame assembly. The frame assembly 11 is mounted on the base 10 by suitable nuts received on fastening means such as threaded weld screws 17a which are affixed one to each of the side plates 14 and 15 and which are received through mounting holes in the base 10. An additional bolt 19 (FIG. 5) threaded into the top plate 16 assists in firmly securing the frame assembly to the base.

An operating coil 20 comprising a winding 21 encapsulated in an insulating compound 22 such as epoxy has a cylindrical opening 23 extending therethrough along the axis of the winding. A pair of power terminals 24 and 25 are mechanically and electrically secured to the ends of the winding 21. A nonconductive generally tubular-shaped spool 26 having an axially-aligned opening and an outer flange 27 near one of its ends is received in the opening 23 of the coil 20, as best illustrated in FIG. 5. The outside diameter of the spool 26 and the diameter of the coil opening 23 are dimensioned to provide adequate clearance for the spool to be easily inserted into the opening but without any excessive looseness.

As illustrated in FIG. 5, the inner wall of the spool 26 has an inwardly-directed annular flange portion 29 defining a section of the spool of reduced inner diameter with respect to the diameters of an upper spool portion 30 and a lower spool portion 31 on either side of the flange portion 29. A generally cylindrically-shaped magnetic flux conducting core 32, preferably fabricated of cold-rolled steel and having an annular shoulder 34 defining a lower core portion 35 of larger diameter than an upper core portion 36 disposed above the shoulder 34, is received in the opening of the spool 26. The diameter of the upper core portion 36 and the inner diameter of the spool 26 at its annular flange portion 29, and likewise the diameter of the lower core portion 35 and the inner diameter of the lower spool portion 31, are dimensioned to provide a slight allowance so that a clearance fit without excessive looseness results between the flange portion 29 and lower portion 31 of the spool and the upper and lower core portions 35 and 36.

Thus, the coil 20, the spool 26, and the core 32 are positioned coaxially with respect to each other, the shoulder 34 of the core cooperating with a downwardly directed shoulder of the inner flange portion 29 to limit the extent of entry of the core 32 into the spool 26, and the outer flange 27 of the spool cooperating with the top edge of the coil 20 to limit the extent of entry of the spool 26 into the opening 23 of the coil.

The top plate 16 of the frame assembly 11 is provided with a circular opening 37 of approximately the same diameter as the inside diameter of the upper portion 30 of the spool 26 and, on the undersurface of the top plate, a shallow annular positioning recess 39 (FIG. 5) surrounds the opening 37. The positioning recess 39 serves to locate and to maintain in proper alignment the upper edge portion of the spool 26 when the spool, coil, and core are secured in the frame assembly 11 as will be explained.

A supporting means such as the core support plate 40, best illustrated in FIG. 2, and having a circular opening 41 of materially lesser diameter than the diameter than the diameter of lower core portion 35, is secured to the frame assembly 11 by suitable nuts received on fastening means such as threaded weld screws 17b which are affixed to the side plates 14 and 15 and extend through holes 42 in the support plate 40. The end of the core 32 at the lower core portion 35 is provided with a shallow conical portion 44, best shown in FIG. 5, which facilitates proper alignment of the core within the opening 37 of the top plate 16. When the support plate 40 is assembled in secured relationship with the frame assembly 11, the upper edge of the circular opening 41 in the support plate bears against the conical portion 44 of the core 32. The annular shoulder 34 of the core, in turn, bears upwardly upon the downwardly-directed shoulder of the inner flange portion 29 of the spool 26 thereby to urge the upper end of the spool firmly against the top plate 16 in the positioning recess 39. Thus the assembly of the spool 26 and the core 32 is firmly secured to the frame assembly 11 by the support plate 40 without the need for any fastening means other than the nuts and cooperating weld screws 17b by which the plate 40 is drawn into the frame assembly 11.

The diameter of the upper core portion 36 is materially less than the opening of the upper portion 30 of the spool 26, thereby leaving clearance space between the upper portions of the core and spool. Likewise, a clearance space is present between the upper core portion 36 and the top plate 16 thereby to provide an air-gap in the magnetic circuit of the relay. A non-magnetic tubular member such as the inductor tube 45, which may be formed of aluminum or hard-drawn copper, is slidably disposed in the aforementioned clearance spaces surrounding the upper core portion 36. The tube 45 carries a contact bridge assembly 46 comprising a pair of electrically-connected movable bridging contacts 47 and an insulating carrier 49. In the preferred embodiment, the contact bridge assembly 46 is mounted on the tube 45 by means of a binding post and screw fastener 50, the assembly 46 being slidably disposed on the binding post together with a helical compression spring 51 which normally urges the contact bridge assembly toward the top end of the inductor tube 45 as shown in FIGS. 4 and 5.

A pair of guide rods 52, fixedly secured in the top plate 16, cooperate with a pair of openings 54 (FIG. 3) in the carrier 49 to guide the contact bridge assembly so as to assure proper alignment of the movable contacts 47 with a pair of complementary stationary contacts carried by a pair of spring steel support members 55. Although the stationary contacts are not visible in the drawings, they are situated as viewed in FIG. 3, at the ends of the support members 55 directly beneath their associated movable bridging contacts 47. When the relay is mounted for use in a motor controller, it is positioned so that the tube 45 is biased by gravity to a position wherein the movable bridging contacts 47 engage their associated stationary contacts.

The contact support members 55 are fixedly mounted by suitable screw fasteners 56 to a contact housing 57 which also supports a pair of terminal members 58. At one end of each terminal member 58 there is provided suitable means for connecting wires from an external control circuit to the terminal members. The other end of

the member 58 is received under one of the screw fasteners 56 and is in electrically conductive relationship with its associated support member 55 and one of the stationary contacts. The housing 57 is secured to the top plate 16 by a pair of screws 60 (FIG. 3).

A cover 61 is provided for the housing 57 to shield the contacts and other relay components from dust and other air-borne contaminants. A pair of spring clips 62 affixed to the housing 57 cooperates with latching shoulders on the cover 61 to removably secure the cover to the housing. An additional cover 64 is secured to the remainder of the relay assembly by a tab portion 65 of the cover 64 which cooperates with a slot 66 in an extension 67 of the support plate 40 and by a bolt 70 which is received through the cover 64 in the top plate 16.

When the cover 64 is secured in place in the relay assembly, portions of the power terminals 24 and 25 of the coil 20 extend through respective holes in the cover thereby to provide access to the coil terminals from the front side of the relay. As shown in FIGS. 1-4, these outwardly extending portions of the terminals 24 and 25 are drilled and tapped to receive bolt fasteners (not shown) of a pair of power leads from an external circuit. As shown in FIG. 2, the terminals 24 and 25 are also drilled and tapped to form threaded openings 24a and 24b therein, respectively; a pair of bolts 71 (FIG. 1) received through the cover 64 in the openings 24a and 24b assists in supporting the coil 20.

The relay functions as described more fully in U.S. Patents 1,980,736 and 2,073,382 to control the commutation of resistance in a motor control circuit.

The relay may be considered as a current transformer with a movable secondary comprising the inductor tube 45 as a single turn winding. The primary of the "transformer" is the winding 21. When current is established in the winding 21, the growing direct current induces a secondary current in the tube 45. Repulsion between the tube 45 and the winding 21 causes the tube to move upwardly thereby to separate the movable and stationary contacts. When the current ceases to grow in the operating winding 21, there is no secondary current in the inductor tube 45, and the tube 45 begins to fall down through flux in the air gap between the upper core portion 36 and the top plate 16.

The flux in the air gap varies in strength directly in accordance with the strength of the current in the winding 21. The rate of return of the movable tube 45 is governed by the strength of the flux in the air gap, being slower when the flux strength is great and being more rapid when the flux strength is small. It is clear therefore that the rate of the return of the inductor tube 45 and hence the length of time required to close the contacts controlled by the movable tube are modified by variations in the strength of the current in the winding 21.

Motion of the tube 45 in the magnetic field causes electric currents to be generated in the tube, opposing the force of gravity tending to move the tube downwardly thereby retarding its downward movement, by which a time delay interval is obtained. At the end of the downward stroke of the tube 45, the movable and stationary contacts are closed.

As previously mentioned, the tube 45 may be formed of aluminum or copper. The use of an aluminum tube in the same relay in place of a copper tube provides, without further adjustment or alteration in the relay structure, an increased time delay interval owing to the decreased electrical conductivity of aluminum as compared to copper.

I claim:

1. In an electromagnetic current-sensing time-limit relay including a magnetic frame having an upper wall, a magnetic core disposed in flux-conductive relationship with said frame, at least one stationary contact, a non-magnetic current-conductive tubular member slidably supported about said core and normally biased toward one position, at least one movable contact carried by said tu-

bular member and in engagement with said stationary contact when said tubular member is in said one position, a coil including a winding surrounding said core and operable upon energization to produce a magnetic flux which causes the tubular member to move quickly away from said one position toward another position wherein said movable contact is out of engagement with said stationary contact, said tubular member, after movement toward said another position and upon continued energization of said winding, being operable to return slowly to said one position, the improvement comprising a non-conductive generally tubular-shaped spool member having an upper portion adapted to bear against said upper wall of said frame and having a downwardly-directed shoulder portion disposed in an axially-aligned opening of the spool member intermediate the ends of said opening, said core being provided with an upwardly-directed shoulder portion intermediate its ends and having a shallow-conical portion at its lower end, core supporting means removably secured to said frame and disposed in spaced relation to said upper wall and having a circular opening therein of materially lesser diameter than the base diameter of said conical portion, said core being coaxially received within the opening of said spool member with the shoulder portion of said core engaging the shoulder portion of said spool member, and the conical portion of said core being received in the circular opening of said supporting means so that an upper edge of the circular opening bears against the surface of said conical portion whereby, when the supporting means is drawn into secured relationship with said frame, said core and spool member are firmly secured relative to each other and to said frame.

2. A relay according to claim 1 wherein a contact housing is removably secured to said upper wall of said frame.

3. A relay according to claim 1 wherein said core supporting means has a forwardly-directed extension having a slot therein and wherein said relay additionally includes a front cover having a downwardly extending tab portion receivable in said slot, said cover being secured to said relay at a front side thereof by receipt of said tab portion in the slot of said extension and by a separate fastener means fastening said cover to said upper wall of said frame.

4. A relay according to claim 1 wherein the tubular member has a generally annular cross-section and is formed of a material selected from the group consisting of copper and aluminum.

5. A relay according to claim 1 wherein said frame is generally U-shaped and said upper wall comprises the right portion of the U.

6. A relay according to claim 5 wherein said core, said frame, and said core supporting means define two magnetic flux paths, each path having a common portion extending through said core, one of said paths extending in loop fashion through said core, one portion of said core supporting means, one leg of said U-shaped frame and one portion of the upper wall of said frame, and the other of said paths extending in loop fashion through said core, the other portion of said core supporting means, the other leg of said U-shaped frame and the other portion of said upper wall, and wherein said magnetic flux path has an air gap therein between said upper wall and the upper end of said core.

7. A relay according to claim 1 wherein said upper wall has a circular opening therein, said opening being of substantially the same diameter as the diameter of the opening of said spool member, said upper wall has a shallow recess surrounding the opening in the upper wall and facing toward said spool member, and said upper portion of said spool member is received in said recess whereby the openings in said wall and spool are maintained in substantial coaxial alignment, said core being disposed substantially coaxially within said openings.

8. A relay according to claim 7 wherein said shoulder portion of said core defines upper and lower core portions,

said upper core portion having a diameter materially less than the diameter of the openings in said spool and said upper wall thereby to define a clearance space between said upper core portion and said upper wall and spool, said tubular member being slidably disposed in said clearance space about said upper core portion.

9. A relay according to claim 1 additionally including a base mounted to said frame at a rear side of said relay, and wherein said winding has a pair of forwardly-facing terminal members at a front side of the relay.

10. A relay according to claim 9 additionally including a cover secured to said relay at the front side thereof, openings in said cover aligned with said terminal members, respectively, so as to permit a portion of said terminal members to extend therethrough exteriorly of the cover, fastening means receivable through said cover and removably secured to the portion of the terminal members interior of the cover thereby to maintain said terminal members in fixed relationship with said cover and to assist in supporting said coil.

11. In an electromagnetic current-sensing time-limit relay including a base, a magnetic frame mounted on a front side of said base by means securing a rear side of the frame thereto, a generally cylindrical magnetic core disposed in flux-conductive relationship with said frame, at least one stationary contact, a non-magnetic current-conductive tubular member slidably supported about said core and normally biased toward one position, at least one movable contact carried by said tubular member and in engagement with said stationary contact when said tubular member is in said one position, and a coil including a winding surrounding said core and operable upon energization to produce a magnetic flux which causes the tubular member to move quickly away from said one position toward another position wherein said movable contact is out of engagement with said stationary contact, said tubular member, after movement toward said another position and upon continued energization of said winding, being operable to return slowly to said one position, the improvement comprising means including a removable support plate clamping said core firmly in place with respect to said frame, said winding having a pair of terminal members spaced from said base and disposed forwardly thereof, so that said terminal members are accessible from the front side of the base.

12. A relay in accordance with claim 11 wherein a cover is secured to said relay at the front side of the frame, said cover having two openings therein aligned with said terminal members, respectively, a portion of each terminal member extending exteriorly of

the cover through its associated opening and the portion of each terminal member interiorly of the cover receiving a bolt fastener threaded into the terminal member from the exterior of the cover to assist in supporting said coil.

13. In an electromagnetic current-sensing time-limit relay including a base, a magnetic frame mounted on a front side of said base by means securing a rear side of the frame thereto, a generally cylindrical magnetic core disposed in flux-conductive relationship with said frame, at least one stationary contact, a non-magnetic current-conductive tubular member slidably supported about said core and normally biased toward one position, at least one movable contact carried by said tubular member and in engagement with said stationary contact when said tubular member is in said one position, and a coil including a winding surrounding said core and having a pair of terminal members adapted for connection to a source of power, said winding being operable upon energization to produce a magnetic flux which causes the tubular member to move quickly away from said one position toward another position wherein said movable contact is out of engagement with said stationary contact, and said tubular member, after movement toward said another position and upon continued energization of said winding, being operable to return slowly to said one position, the improvement comprising a cover secured to said relay at the front side of the frame, said terminal members being spaced from said base and disposed forwardly thereof so as to provide access to said terminal members from the front side of said base, and said cover having two openings therein aligned with said terminal members, respectively, a portion of each terminal member extending exteriorly of the cover through its associated opening and the portion of each terminal member interiorly of the cover receiving a bolt fastener threaded into the terminal member from the exterior of the cover to assist in supporting said coil.
